(54) **PEGS, SHOE, SPLITTING**

(76) Inventor: **Mark Wilder**

Mark Wilder, of Peterborough, New Hampshire
Letters Patent.

The schedule referred to in these Letters Patent and making part of the same, containing a description in the words of the said Mark Wilder, himself, of his improvement in a machine for cutting or splitting shoe pegs.

To all to whom these presents shall come.

Be it known that I, Mark Wilder, of Peterborough in the County of Hillsborough and State of New Hampshire, have invented a new and useful improvement in a machine for cutting or splitting shoe pegs, and that the following is a full and exact description of the construction and operation of the said machine as invented or improved by me.

The machine consists of a substantial oblong bed, hewn squared to be strong enough which project sufficiently far to receive the tenons of four upright corner posts of a strong frame connected at top by suitable caps, & cross pieces, that supports the machinery hereinafter described; in the middle of the upper side of the bed piece running its whole length is a groove, in which slides a corresponding tongue made on the under side of a sliding carriage or platform of the same length as the bed, upon the front end of which the block to be cut, into pegs, is placed a flat circular metallic disk or wheel, having a hole at its centre in the under side that receives a steady pin, fastened in the upper face of the carriage, being first placed under said block so as to form a level solid bearing for the block, near the front margin of the disk several fixed points, or screws are placed, which range in a short arch of a circle concentric to said wheel and against which the block to be cut is made to bear by means of a very narrow strip connected to one of said screws, and which after being passed around the block is led over a small horizontal friction roller, at the front margin of the disk, having a weight attached to the end, the operation of which is to draw the block against the fixed points and prevent it from separating, until the pegs are completed, a small projection is made on the front end of the carriage on which the weight may

is lowered whilst the operator is replacing the blocks, along the middle of the rear half of the carriage is a catch-bar or rack operated by a double-pall so as to advance the carriage as follows; from a horizontal crop-shaft which has its bearings in two boxes projecting from the front side of a crop-rail of the back portion of the frame descends an arm to a point nearly level with the rail, the arm being marked through the shaft, and confined by a side-screw, so as to admit of being lengthened or shortened, for the purpose of adjusting the feed to suit pegs of different sizes. To the foot of the arm the pall which is of ordinary make is attached by a pin on which it works as a centre, the pall itself extending forward, horizontally, immediately under this pall is another one end of which is attached to the lower side of the back crop-rail first mentioned by a thumb screw, and the other extending to near the end of the upper pall is turned down thus serving as a lower pall or held, these palls are kept down by a weighted crop lever having a left strap or staple on the lower side through which the pall-puffs, and are thrown out of gear by raising the end of a second or transvers lever at the front or leading side of the machine within reach of the operator, from the front side of the shaft is a long arm that extends forward and attaches by a shifting screw so as to regulate the feed to a limit or arm from the knife-shaft by the upward and downward motion of which the palls are operated and carriage is advanced the receding motion of the carriage being produced by a ~~chain~~ and weight attached to the back end thereof operating over a pulley. The knife which is straight and tempered steel, ground with a double bevel to a smooth not a sharp edge, has a broad flat tang or strap rising from the middle of the back the whole resembling a letter T this tang enters a slot or groove in the lower end of the knife-shaft which latter is a flat upright-shaft that slides up and down midway between the front posts, through two suitable crop pieces or guides placed one immediately above the other at the front of the frame and is secured by screw bolts, that pass through two oblong holes, in the tang so as to admit of the knife being lowered or raised by means of a wedge or key that passes through the shaft acting against the upper end of the tang, and thus adjust it to the length of the pegs to be split, immediately in rear of the knife from the

under side of the lower guide piece by two short screws mortised through said piece is suspended a semicircular guard in a horizontal position just over the block to be split, the object of which is to prevent the block from casting up at the back edge when the front is operated on by the knife. To the upper end of the knife shaft is attached a toggle joint lever that extends to the top of the frame through two guide rails or bars, which toggle joint is worked by a horizontal bar, attached to the crank of the operating shaft, the length the crank being such as to cause by each revolution thereof two upward and two downward motions of the knife shaft, the operating shaft being also supplied with a balance wheel, and a fast and loose pulley by which the power is applied to the machine, by a shifting strap. Also from a small rocking shaft fixed on the front face of the cap rail a lever descends to within reach of the operator, it has a transverse bar a short distance above the toggle joint notched out of the width of the toggle lever, for the purpose of pressing the toggle lever to one side, and thereby raising the knife when the machine is stopped, to replace the block. Operation.

The blocks after being pointed by a grooving tool in the ordinary way or by any other means are successively placed on the circular disk and the confining strap put around them — the weighted lever is then raised, and the carriage recedes by the operation of the chord & weight at the rear end.

The disk is then turned till either set of grooves in the block stand parallel to the edge of the knife. The operating shaft is then put in revolution and the knife rises and descends twice for every turn of the crank, each time it rises operating on the palls so as to advance the carriage and block, the thickness of one peg, until the whole breadth of the block is traversed by which operation the pegs are rived or scored in one direction and continue to be held together by the strap, the weighted lever is then raised and the carriage recedes, the disk is now turned one fourth round which brings the remaining grooves parallel with the edge of the knife and the machine being again set in revolution, the block is traversed in a similar manner by the knife and the block being finished is removed and replaced by another and so on. after being thus prepared the pegs are sorted in the usual way. The dimensions

of the machine being variable to suit circumstance. I have not mentioned any in the foregoing description altho I have found the following to answer well in practice, frame about 9 feet high 3 $\frac{1}{2}$ long 3 wide bed pine 2 ft. 8 wide, carriage 17 inches wide joints of the toggle about 2 $\frac{1}{2}$ feet each.

Now what I claim as new and as my invention for which I ask Letters Patent, is the toggle joint lever & knife shaft, the revolving disk and spindles together with the pulley by which the feeding is effected the whole operating in combination for the purposes and in the manner here in set forth, and described. In testifying that the foregoing is a true specification of my said improvement I have hereunto set my hand this 14th day of July 1835.
